INVENTOR.

William T. Pierce

BY

Frank Lescow

ATTORNEY.

UNITED STATES PATENT OFFICE.

WILLIAM T. PIERCE, OF NORTH CAMBRIDGE, MASSACHUSETTS.

PICTURE-HANGER.

1,372,543.

Specification of Letters Patent. Patented Mar. 22, 1921.

Application filed March 22, 1920. Serial No. 367,604.

To all whom it may concern:

Be it known that I, WILLIAM T. PIERCE, a citizen of the United States, residing at 5 North Cambridge, in the county of Middlesex, in the State of Massachusetts, have invented a certain new and useful Improvement in Picture-Hangers, of which the following is a specification, reference being had 10 to the accompanying drawings.

This invention relates to hooks for use in hanging pictures against walls, my object being to provide simple and inexpensive means, embodied in said hanger, for concealing the hook proper; said concealing means being of such a nature that it will be ornamental and will preferably harmonize with the picture which is supported by the hanger.

20 With these desirable objects in mind, I have provided the annexed drawings, in which Figure 1 is a front face view of a hanger embodying my present improvement as it appears when in use, that is to say, 25 when it is supporting a picture, and Fig. 2 is an edge view of the same. Fig. 3 is a relatively enlarged edge view of the hanger and Fig. 4 is a front face view of the metal hook.

30 Referring to these drawings, the letter *a* indicates a section of molding of the type commonly provided at or near the ceiling of a room and *b* denotes the side wall of the room.

35 My improved hanger consists essentially of a metal hook *h* one leg of which is provided with an extension constituting a supporting bar, to secure it to the wall or other means, and which, in the embodiment of my 40 invention shown in the drawings, is preferably of sinuous shape so as to make it somewhat spring acting, and the upper part of which may be provided with a rearward curved or hook shaped extension *c*, which is 45 adapted to fit, and hang upon, the upper edge portion of the molding *a*, or said hook *h* may, if desired, be fastened to the side wall *b* by means of a nail *d* driven through a hole *e*, as will be understood by reference 50 to Fig. 3, in which such a nail is shown in dotted outline.

Secured to the outer face of the hook member *h* is a card or plate *f* which is of such size that it covers, or nearly covers, and 55 hides the said hook member, said card being

permanently secured to the hook, as here shown, by a rivet or clip *g*.

Upon the exposed face of the card *f* I, preferably, print, or otherwise display thereon, a picture, medallion, initial, monogram or other insignia which will harmonize with the picture which is to be suspended from the hanger, as for example, if the picture be a tiger, or other example of the genus feline, the picture on the card *f* may represent the head of a cat.

The lower portion of the supporting member is upturned to form the hook *h* and the card *f* is preferably cut away, or rather slotted to provide an opening through which the hook *h* may project (see Fig. 3) and also a tongue *i* which is formed by striking out the slotted part of the card, and being bent upward is located immediately in front of the otherwise exposed hook *h*; the arrangement of the described parts being such that, when viewed in front, the continuity of the picture on card *f* is practically unbroken (see Fig. 1).

In the operation of hanging a picture *h*, a cord or wire *m* is looped over the metal hook *h*, as seen in Figs. 1, 2, and 3, and said cord incloses also the tongue, if the card be slotted as above described.

My described device may be produced very cheaply; it may be utilized with ordinary so called "picture moldings" and it provides a specially appropriate and pleasing form of hanger.

Having thus described my invention, I claim:

1. In a picture hanger the combination with a supporting bar, and a forwardly directed hook at one end of said bar, and a covering member superposed upon the hook-carrying side of said bar, and substantially coextensive therewith, of an unbendable connection at one end portion of said covering member, and securing said end portion in contact with said bar, a rearwardly curved terminal attaching portion integral with said bar adjacent said unbendable connection.

2. In a picture hanger the combination with a sinuous supporting bar, and a hook at one end of said bar, and a covering member superposed upon the hook carrying surface of said bar, and substantially coextensive with said surface, of an unbendable connection at one end portion of said member,

and securing said portion in contact with said bar, a terminal hook shaped portion on said bar adjacent the unbendable connection and bent away from the first mentioned hook shaped portion, and adapted for suspending said supporting bar.

3. In a device of the class described in combination, a sinuous supporting bar, and a hook at one end of said bar, a substantially straight covering member superposed upon

the hook-carrying surface of said bar, substantially unbendable connecting means at one end portion of said member and securing said portion in contact with the corresponding part of said bar, and a slotted portion on said member surrounding said hook, and covering means projecting from said slotted portion and superposed upon said hook and adapted for concealing the same. 15

WILLIAM T. PIERCE.
